Inventor:
John R. Beckett
by Clyde L. Rogers
his Atty.

UNITED STATES PATENT OFFICE.

JOHN R. BECKETT, OF SOMERVILLE, MASSACHUSETTS.

TRUING DEVICE FOR GRINDING DISKS.

Application filed July 17, 1919. Serial No. 311,531.

To all whom it may concern:

Be it known that I, JOHN R. BECKETT, a citizen of the United States, and resident of Somerville, county of Middlesex, Commonwealth of Massachusetts, have invented an Improvement in Truing Devices for Grinding Disks, of which the following description, in connection with the accompanying drawings, is a specification, like characters on the drawings representing like parts in each of the several views.

The invention relates to devices for truing grinding disks or like rotary tools with operative peripheries either V-shaped in cross section or with more or less of flattened peripheral surfaces between the beveled peripheral edges. A principal object of the invention is to provide a truing device that may be quickly and easily adjusted and set for gauging and truing the beveled edge at either side of the tool or a flattened intermediate peripheral portion with the use of a single diamond point or like truing element. A further object is to provide a self-contained unitary attachment adapted to be detachably applied to a grinding head for truing up the grinding disk as required. The foregoing and other objects and advantages of the invention will more fully appear from the following detailed description, and the distinctive features of novelty will be pointed out in the appended claims.

Referring to the drawings:

Fig. 1 is a side elevation of a grinding head equipped with my invention;

Fig. 2 is a vertical section of the truing device and taken approximately on line 2—2 of Fig. 1;

Fig. 3 is a bottom plan view with a portion broken away of the grinding head equipped with the invention;

Fig. 4 is a detail section on line 4—4 of Fig. 2 looking in the direction of the arrows; and

Fig. 5 is a diagrammatic plan illustrating the use of the truing device.

10 indicates a bracket frame equipped with a base 10^a adapted to be secured, preferably for angular adjustment, to a table or slide rest by means of a clamp bolt engaged in the threaded socket 10^b thereof. This bracket frame is also equipped with spaced apart uprights 10^c, 10^d having bearings for an arbor 11 having fixed at a projecting end thereof a grinding disk 12 and having also fixed thereon between the uprights 10^c, 10^d

a driving pulley 13. The grinding disk 12 is as shown in Fig. 1 formed with peripheral edges V-shaped in cross section presenting beveled grinding sides 12^a, 12^b which the truing device of the invention is adapted to engage and operate on. In accordance with my invention the bracket frame 10 is equipped underneath the grinding disk with an undercut way 14 in which is slidably fitted a tongue 15 projecting from a head 16, this tongue being adapted to be clamped in adjusted position by any suitable means shown as a screw 17 engaging a follower or gib 18 at one side of said undercut way. 70 Mounted to turn in the head 16 is a vertical hollow post 19 having fixed at its lower end underneath the head 16 a plate segment 20 by means of a key 20^a. This segment is formed with an arcuate undercut slot 21 in 75 which are adjustably fitted headed bolts 22, 23 adapted to be clamped thereto in any adjusted position and each bearing a transversely extending adjustable threaded pin 24. The clamp bolts 22, 23 bearing the pins 24 are 80 so set in the slot 21 that the projecting extremities of the pins 24 are adapted to engage a stop pin 25 set into and depending from the head 16 to limit adjustably the turning movement of the post 19 and thus 85 define limiting positions of the diamond point or like truing device which is borne by the post 19 as now to be explained. The post 19 has its top laterally extended to constitute a slide way 26 with undercut sides 90 and with which is slidably engaged a carriage 27. This carriage has fixed underneath the same at one side thereof a rack bar 28 which is engaged by a pinion 29 fixed at the top of a shaft 30 which is vertically journaled in the hollow post 19 and is equipped with a stem 30^a projecting downwardly below the post 19 with an operating head 31 at the extremity thereof which may be knurled to constitute a better finger hold. 95 The carriage 27 has fitted to move transversely on the top surface thereof a slide rest 32 in which is threaded an operating stem 33 having at its inner portion a swivel engagement 34 with the carriage 27 to hold the same from endwise movement. This stem has a knurled head 35 for actuation thereof. The slide rest 32 has fitted in a socket 32^a the stem of a tool holder 36 equipped with a socket to hold a truing tool 37 which may be diamond pointed as indicated at 37^a. With the described mounting 100

105

110

of the truing tool 37 it will be noted that said tool may be adjusted angularly by operating the segment plate 20 and with the locating pins 24 co-operative with the stop 5 pin 25, so that said tool as moved by the actuation of the carriage 27 along the slide way 26, will engage and true each side 12°, 12° of a V-edged grinding disk, these two adjusted positions of the truing tool being 10 indicated at 370, 371 respectively. Likewise the tool may be set so as to traverse across a flattened peripheral edge 12° of a grinding disk which may embody such an outline, as is required for certain uses, the position of 15 the tool in this case being indicated at 372 and the slide way 26 being then set parallel with the axis of the grinding disk. Thus the slide way 26 may be quickly and easily located and alined for truing movement of 20 the tool in any required direction, and the tool may then be moved to traverse it over the different portions of the surface to be trued by operating the knurled head 31. The required setting of the tool transversely 25 inward to bring it into proper operative contact with the surface to be trued may be readily effected in any adjusted position of the tool mounting by actuating the knurled head 35. I am thus enabled to utilize a single 30 diamond pointed or like truing tool for truing up grinding disks of any form or outline that may be encountered and the necessary setting for any particular grinding disk can be quickly and easily effected. The bracket 35 frame 10 with its base 10a bearing the grinding disk and adapted to receive the truing device as described, is preferably clamped to a suitable slide or carriage mounting so as to be angularly adjustable about an axis line 40 x—x as indicated in Fig. 2, this axis being the axial center of the threaded socket 10b, and the entire device being adapted for clamping to its support in like manner as illustrated for example in my prior application 45 for thread milling attachment for lathes, Serial No. 257,967 filed October 14, 1918, though it will be understood that this manner of mounting is merely illustrative. I am aware that the invention may be embodied in other specific forms without departing from the spirit or essential attributes thereof and I therefore desire the present embodiment to be considered in all respects as illustrative and not restrictive, reference being had to the appended claims 50 55

rather than to the foregoing description to indicate the scope of the invention.

Having described my invention, what I claim as new and desire to secure by Letters Patent is:

1. The combination with a grinding disk, of a truing device therefor comprising a carriage support mounted for angular adjustment to extend diagonally at either side of said disk at will, a carriage bearing a 65 truing tool mounted for movement on said support and equipped with an actuating device coaxial with the axis of adjustment of said support, and means for adjusting the tool transversely on said carriage. 70

2. A truing device for grinding disks, comprising a bracket mounting adapted to be detachably applied to a grinding tool frame, a support mounted for angular adjustment in said bracket with adjustable 75 stops for variably and positively limiting such movement, a carriage mounted to slide on said support with means for actuating the same, and a truing tool mounted on said carriage to be operated transversely by the 80 movement thereof.

3. A truing device for grinding disks, comprising a bracket mounting adapted to be applied to a grinding tool frame, a post support mounted for angular adjustment in 85 said bracket with adjustable limiting means, a carriage mounted to slide on the top of said post equipped with a rack and pinion actuating device having an operating stem extending through said post, and a truing tool 90 mounted on said carriage for adjustment in a direction transverse of the carriage movement.

4. The combination with a frame having a grinding disk journaled therein, of means 95 for truing such disk comprising a bracket detachably and adjustably applied to such frame, a post mounted to turn in said bracket with provision for predetermined angular adjustment, a carriage mounted to 100 slide on the top of said post with a rack and pinion actuating device having an operating stem extending through said post, and a tool holder mounted for adjustment on said carriage in a direction transverse of the carriage movement. 105

In testimony whereof I have signed my name to this specification.

JOHN R. BECKETT.
